UNITED STATES PATENT OFFICE.

GILBERT A. COLBY, OF CHICAGO, ILLINOIS, ASSIGNOR, BY MESNE ASSIGNMENTS, TO M. COCHRAN ARMOUR, OF SAME PLACE.

STEAM-BOILER FEEDER.

SPECIFICATION forming part of Letters Patent No. 387,553, dated August 7, 1883.

Application filed June 27, 1887. Serial No. 242,552. (No model.)

To all whom it may concern:

Be it known that I, GILBERT A. COLBY, of Chicago, in the county of Cook and State of Illinois, have invented certain new and useful Improvements in Steam-Boiler Feeders; and I do hereby declare that the following is a full, clear, and exact description thereof, reference being had to the accompanying drawings, and to the letters of reference marked 10 thereon, which form a part of this specification.

This invention relates to water-feeding apparatus of that kind in which the supply of water to the boiler is controlled by means of 15 a float within the boiler.

The invention consists in the matters hereinafter described, and pointed out in the appended claims.

My invention is herein shown as applied to 20 a water-tube boiler, or one in which the water is held in a plurality of tubes exposed to the action of the fire, a special chamber or float-drum being provided for the float of the apparatus. The main features of the invention may, however, be applied to boilers of other kinds. The 25 novel features of construction in the water-tube boiler herein shown are described and claimed in a separate application, Serial No. 260,165, filed in the United States Patent Office 30 January 9, 1888.

In the accompanying drawings illustrating 35 my invention, Figure 1 is a vertical longitudinal section of a boiler constructed in accordance with my invention. Fig. 2 is an end view of the boiler, showing the end thereof which is at the right-hand side of Fig. 1. Fig. 3 is a cross-sectional view of the same, taken upon line $x-x$ of Fig. 1. Fig. 4 is a detail horizontal section of a float and tube or chamber containing the same, taken upon line $y-y$ of Fig. 1. Fig. 5 is a detail section taken upon line $x-x$ of Fig. 4. Fig. 6 is a detail section taken upon line $z-z$ of Fig. 1. Fig. 7 is a detail section of the end portion of the float and 40 adjacent part of the float casing or chamber, taken upon line $x-x$ of Fig. 5. Fig. 8 is a detail section taken upon line $x-x$ of Fig. 2, showing devices for supporting the steam-header from the water-head of the boiler.

50 As illustrated in the said drawings, A A'

are two vertical water-heads arranged parallel with each other, or nearly so, at opposite ends of the boiler, and each consisting of parallel plates $a a$, connected by studs $a' a'$ in a familiar manner.

B B indicate a series of water pipes or tubes arranged in an inclined position and connected at their opposite ends with and extending between the water-heads A A'. The tubes B B are located at the lower part of the 6c boiler, adjacent to the furnace, so that the water therein is exposed to the most intense heat from the furnace-fire. Above the tubes B B is located a second series of tubes, C C C, which are arranged horizontally, and are also connected at both ends with the water-heads A A'. Said tubes B B B and C C C, together with the said water-heads A and A', form a closed circuit in which the water is adapted to freely circulate, the water in the inclined 70 tubes B B rising as it is heated and flowing upwardly in said tubes to the water-head A, from which it passes through the horizontal tubes C C C backwardly to the water-head A', and then downwardly into the tubes B B B.

The water-head A' terminates a short distance above the level of the pipes C C C; but the head A is extended considerably above said pipes, and connected therewith is a third series of pipes, D D D, located above the pipes 80 C C C. At the end of the boiler, adjacent to the water-head A', is located a transversely-arranged horizontal steam chamber or header, E, with which the ends of the several steam pipes or tubes D are connected.

The water-line of the boiler is located at or slightly above the upper water-pipes, C C C, and the space within the water-head A, above said pipes C C C, together with the said pipes D D D and the header E, form the steam-space 90 of the boiler, said pipes D D D being exposed to the products of combustion from the furnace and acting as superheating-pipes to dry the steam. Steam is taken from the boiler by means of an exit-pipe, E', connected with the header E, and a safety-valve, when employed, may be conveniently located upon and connected with the said header E.

In order to afford a direct passage for steam generated in the upper part of the water-head 100

A' to the steam-header E, a pipe, E², connects the upper part of the said water-head A' above the water-line therein with the said header E. Inasmuch as there is liable to be more or less 5 relative movement between the header E and the water-head A', owing to an unequal degree of expansion in the pipes D D, connecting said parts with the water-head A, I preferably make the pipe E² of considerable length 10 and dispose it in an inclined position, as clearly shown in Fig. 2, so that it may bend or yield in the movement of the parts without bringing undestrain upon the pipe or its connections.

15 The header E in the particular construction thereof herein illustrated is formed by an integral casting of rectangular cross-section, the inner vertical side wall of which is apertured to receive the pipes D D, which are secured by 20 being expanded therein in a familiar manner. Said header is provided at its outer surface with holes closed by removable screw-plugs e e, which afford access to the tubes for cleaning the same and other purposes.

25 In the particular construction of the parts herein shown the pipes D D are arranged in two horizontal rows, with one row above and parallel with the other row, and the header E is provided with a horizontal partition, E³, 30 dividing the said header into two parts or chambers connected, respectively, with the two sets of pipes. The exit-pipe E' is connected with the header at one end of the latter. Said header is provided at its end at which the 35 exit-pipe is attached with an upwardly-extending part or dome, E⁴, beneath which is located a vertical partition, e', forming an extension of the partition E³, said vertical partition being extended past the partition E³ downwardly to the bottom wall of the header. Said partition e' prevents the direct flow of steam toward the steam-exit pipe and causes the said steam to pass upwardly through the said elevated part E⁴ before it passes out through 40 said exit-pipe. The partition E³ terminates short of the end wall of the header, at the end of the latter remote from the exit-pipe, whereby the steam entering the lower part of the header E from the lower row of steam-pipes 45 D is caused to pass beneath the partition E³ to the end of the header and then around the end of said partition and upwardly into the upper compartment of the header, from which it makes its escape over the partition e' with the 50 steam from the upper row of pipes, as clearly shown in the drawings, Fig. 2. The object of the partitions E³ and e' is to cause the steam to take an indirect course in its passage to the exit-pipe, so as to effect the separation of water from the steam and thus insure the passage of perfectly dry steam from the boiler.

55 I have herein shown the header E as located immediately over and as supported by the water-head A'. To provide for any shifting or 60 sliding of the header upon the water-head, as is liable to occur by reason of unequal expansion

of the tubes, as hereinbefore stated, I have herein shown as placed between said water-head A' and header E two horizontal flat plates or castings, G G', between which plates 70 G G' are placed a roller or rollers, g, allowing free relative movement of the plates. In order to form a close joint between the plates G and G', one of the plates, as G, is provided with flanges g', coming close to the lower surface of the plate G', but without touching it. The said plates G and G' are shown as held in place upon the water-head A' and header E by being provided with suitable grooves or 75 sockets to receive the said parts in the manner 80 clearly shown in Fig. 8.

H is a feed-water pipe, which I have herein shown as arranged to enter the water-head A' at a point above the tubes B B and below the tubes C C.

85 H' is a blow-off valve connected with the water-head A' at a point below the water-tubes B B. The said water-head A' is desirably extended considerably below the water-tubes, so as to form a receptacle for mud and sediment 90 with which the blow-off valve is connected.

I is a horizontally-arranged tube or cylinder located between the water-heads A and A', and connected with the latter by short tubes or thimbles i i, said cylinder being arranged adjacent to the upper row of water-pipes C, and in such vertical position that the water-level of the boiler passes therethrough. Within the said cylinder is located a float, J, which is preferably made of considerable length in proportion to its diameter, and is desirably arranged to extend from end to end of the cylinder I. The float J is sustained in position in the cylinder by means of two arms, j j, having pivotal support upon the end walls, I', of the cylinder I. The pivotal connection between the arm j at one end of the float and the cylinder-head I' is formed by a straight pin, j', inserted in opposing recesses formed in the said head I' and in the end of the arm, said recesses being extended only partially through the arm and the head, so that the pin j' is held from endwise movement, while at the same time the making of any joints liable to permit the escape of water or steam at this point is 110 avoided. The supporting-arm j of the float, at the opposite end of the latter, is pivotally supported by means of a hollow or tubular shaft, j², which extends through a stuffing box or gland, I², in the end wall I' of the cylinder 115 to a point outside of the latter. Secured to the said shaft outside of the cylinder is a lever, J', by means of which the motion of the float is communicated to the controlling device employed in connection with the feed-water supply apparatus for regulating the inflow of feed-water to the boiler. I have not herein shown any feed device, inasmuch as any one of a number of well-known forms of such devices may be employed, and the feed devices themselves 120 have no bearing upon the present invention, which relates solely to features of construction 125

of and in the boiler itself. Upon the said lever J' is placed a weight, J², to counterbalance the weight of the float J.

Instead of attempting to make the float J steam and water tight, as heretofore common, I provide the said float in its upper part with an opening, j³, through which steam may freely enter the said float, and in order to provide means for conveniently discharging the water 10 which may find its way into the float by condensation of steam therein or otherwise I provide a small passage, j⁴, leading from the bottom of the float through the supporting arm j to the shaft j², which shaft is made hollow or 15 tubular to form a continuation of the said passage j⁴. Upon the outer end of the said shaft j² is placed a stop-cock, J³. This stop-cock is commonly kept closed; but when it is desired to discharge from the float any water which 20 may have entered the latter the said stop-cock is opened and such water will be forced therefrom by the steam-pressure of the boiler. The presence of water in the float at any time may be readily detected by opening the cock J³.

The float lever J' is arranged to extend outwardly through a suitable opening in the furnace-wall, which opening is shown in the drawings as constructed to also afford convenient access to the stop-cock J³. I have herein 25 shown an open-ended metal casing or shell, K, as inserted in the furnace-wall, with its inner edges in contact with the end of the cylinder I and the thimble i, the said cylinder in this 30 case being located adjacent to the side wall of the furnace. The said casing K prevents the 35 heated products of combustion within the furnace from reaching the shaft j², the gland I², and the stop-cock, while at the same time allowing the said stop-cock to be reached and 40 manipulated without opening the furnace or boiler-casing.

As a convenient means of constructing the float J, I make the latter of a straight cylinder, J⁴, closed at its ends by circular plates J⁵, 45 screw-threaded upon their edges to enter the screw-threaded ends of the tubular body of the float. I also preferably cast the arm j integral with the head J⁵, adjacent thereto, and form the passage j⁴ by boring endwise through 50 the arm and crosswise through the head in the manner clearly shown in the detail section, Fig. 7. At its outer end the arm j is provided with a hub, j⁶, having a socket to receive the tubular shaft j², said shaft being 55 secured therein by a set-screw in the manner shown. The passage j⁴ is bored into the said socket, thus affording communication between the said passage and the tubular shaft.

The employment of a long float-chamber, I, 60 located within the furnace, has the advantage of affording considerable additional heating-surface in the boiler. The use of a float very long in proportion to its diameter is of advantage also, inasmuch as a float of this kind is 65 influenced to little extent by local disturbances of the water in different parts of the

float-chamber, but always maintains a position corresponding with the average level of the water at any particular time.

The boiler constructed in the manner described may be used in connection with a furnace constructed in any suitable or convenient manner. The furnace herein illustrated consists of side walls, M M, located at the sides of the several water and steam tubes, a top 70 wall, M', extending over the top of the super-heating tubes D D, and front and rear walls, M² M³, sustaining the water-heads A A'. A fire-box, N, is formed by means of a bridge-wall, N'. The products of combustion from 75 the furnace are caused to take a circuitous path through or about the tubes in their passage to the exit smoke-pipe N² by means of a horizontal position, O, extending from the front water-head, A, of the boiler backwardly over 80 the upper water-tubes, D, to a point near the rear water-head, A', where it is connected with a vertical wall, O', and extends downwardly to a point beneath the lowermost row of tubes B. A second vertical wall, O², extends from the top of the bridge-wall upwardly 85 to a point near the horizontal partition O, spaces being left between the upper edge of the said wall O² and the said partition O and between the bottom of the wall O' and the 90 floor of the furnace for the passage of the flames and heated products of combustion over or around the said walls in the direction indicated by the arrows, Fig. 1. After passing to the rear of the wall O' the said products of 95 combustion pass into the space above the partition O, and then forwardly to the exit smoke-pipe N², which is located near the front of the boiler. In this construction the hottest 100 part of the flames and products of combustion coming directly from the fire are concentrated upon the water-tubes B and C, while the steam superheating-pipes D D are subjected to the action of the said heated products of combustion after the latter have passed 105 over the water-pipes, in the manner clearly shown in the drawings.

I have herein shown the water-head A' as sustained upon two metal plates, P P', having anti-friction rollers p p between them, thereby 110 allowing the said water-head to move freely upon the supporting-wall M³ as the tubes B B and C C C expand and contract, these plates or rollers being made substantially like those above described as being located between the said water-head A' and the header E. 115

I claim as my invention—

1. The combination, with the vertical water-heads A A', a series of inclined water-tubes, B B B, connected at their opposite ends with 120 the said water-heads, and a second series of horizontal water-tubes, C C C, also connected with the said water-heads, of a horizontal float-chamber, I, located between the said heads and communicating with the water-space of the boiler, substantially as described. 125

2. The combination, with a boiler compris-

ing vertical water-heads A A', and water-tubes connected at their opposite ends with said heads, and a furnace-casing surrounding said boiler, of a float-chamber, I, connected at its 5 opposite ends with the said heads and located at a point adjacent to the side wall of the boiler-casing, a float within said chamber, and a pivotal support for the float provided with an arm, J', extending outwardly through 10 an opening in the boiler-casing, substantially as described.

3. The combination, with a boiler-casing and boiler comprising a float-chamber, I, of a float located within said chamber, a pivotal 15 support for the float extending through the wall of the float-chamber and provided with an arm, J', and a shell, K, inserted in the boiler-casing and extending inwardly to and around the pivotal support of the float at the 20 point where it emerges from the float-chamber, substantially as described.

4. The combination, with the float-chamber of a boiler, of a float provided with a steam-opening at its upper part, a pivotal support 25 for the float extending through the wall of the float-chamber and provided with an arm rigidly attached to the float, said pivotal support and arm being provided with a passage communicating with the interior of the float at 30 the bottom part thereof and with the open air, and a hand-valve located in said passage ex-

terior to the float-chamber, whereby the said passage may be kept normally closed to prevent escape of steam from the boiler and may be opened at desired times to allow the escape 35 of water from the float, substantially as described.

5. The combination, with a horizontally-ar- ranged float-chamber, of a cylindric horizontally-arranged float extending through the 40 greater part of the length of the said float-chamber, and a pivoted supporting arm or arms for the said float, substantially as described.

6. The combination, with a horizontally-ar- ranged float-chamber, of a float and support- 45 ing-arms for the float attached to opposite ends of the latter and having separate pivotal connection with opposite end walls of the float-chamber, substantially as described.

7. The combination, with a horizontally-ar- ranged float-chamber, of a cylindric float con- 50 sisting of a hollow cylinder and metal disks or end walls secured in the end of said cylinder and provided with supporting-arms cast in- tegral therewith, substantially as described. 55

In testimony that I claim the foregoing as my invention I affix my signature in presence of two witnesses.

GILBERT A. COLBY.
